UNITED STATES PATENT OFFICE.

CHARLES P. TRIMBLE, OF PITTSBURGH, PENNSYLVANIA, ASSIGNOR TO FORT PITT BEDDING COMPANY, OF PITTSBURGH, PENNSYLVANIA, A CORPORATION OF PENNSYLVANIA.

CUSHION SEAT AND THE LIKE.

Application filed March 14, 1923. Serial No. 625,115.

To all whom it may concern:

Be it known that I, CHARLES P. TRIMBLE, a citizen of the United States, residing at Pittsburgh, in the county of Allegheny and State of Pennsylvania, have invented certain new and useful Improvements in Cushion Seats and the like, of which the following is a specification.

This invention relates to cushion seats and the like and it comprises a top and a bottom frame, advantageously of wire, the bottom frame being provided with transverse, preferably longitudinally arched, channel bars or angle irons, each provided with a longitudinal reinforcing boss along the top and with sets of perforations through the side walls thereof, the channel bar at each end being arched transversely and flattened, the boss of the channel bar continuing over the transversely arched portion, and the flattened ends being securely wrapped around opposite sides of the bottom frame, together with coil springs attached to the top border frame and to each other by means of clips or the like and attached at the bottom to the channel bars through insertion of the lowermost coil of each spring through a set of perforations in the bars; all as more fully hereinafter set forth and as claimed.

Among other objects of my invention is the provision of an extremely simple seat or cushion of great rigidity and strength and the provision of a cushion, the parts of which can be easily and quickly assembled. As will be more fully described in detail, the frame together with the spring supporting channel bars may all be made of stamped or pressed metal and at the same time the parts may be assembled to make a strong rigid construction. The channel bars are particularly designed to afford the greatest possible resistance to stresses and strains.

In the accompanying drawings showing one form of a specific embodiment of my invention and in the several views of which similar reference numerals designate corresponding parts,

Fig. 1 is a side plan view of the cushion partly in section;

Fig. 2 is a detailed segmental side view of the channel bar in elevation;

Fig. 3 is a bottom plan view of the channel bar attached to the side rail;

Fig. 4 is an end view of Fig. 3;

Fig. 5 is a vertical transverse section along line 5—5 of Fig. 2; and

Fig. 6 is an end view of the section of the lower border wire showing a modified form of means for preventing longitudinal movement of the channel irons.

Referring to the drawing reference numeral 1 designates the top border frame and 2 indicates the bottom frame both of which may be made of wire or the like, while reference numeral 3 indicates the outer cover of leather or the like, 4 the upholstering material of hair or felt and 5 the under cloth of canvas or the like which together with the leather is securely clamped around the lower border wire 2. The clamps for this purpose may be of any type, such as clips shown and claimed in my copending application, Serial No. 586,223.

Mounted to engage opposite sides of the lower frame wire 2 are a plurality of longitudinally arched angle irons 6 of approximately inverted U or V shape each having a longitudinal reinforcing boss 7 along its top. The extremities of the bars are flattened as at 8, perforated as at 9 and arched transversely as at 10, the boss 7 of the channel bar continuing over the transversely arched portion as at 11. Instead of forming the boss 11 as a continuation of the boss 7, it may be exaggerated somewhat in the stamping operation in such a way as to give greater strength to this portion of the bar. The flattened extremities 8 are wrapped around the lower border wire 2 by means of a suitable tool, the space formed by the arch 10 giving sufficient room for operation of the tool and also forming a recess in which the lower ends 12 of the leather and canvas may rest and be held away from the bottom of the seat. When the flattened extremities 8 of the channel bar are wrapped around the bottom border wire 2, there may be formed on the latter, through the perforations 9, swaged portions 13. These may be made by means of a punch or the like upsetting the metal around the punch hole and resulting in a projection which secures the channel bars against longitudinal movement on the border wire. The channel irons may be made of stamped or pressed metal and are especially strong in construction due not only to the channel iron feature, itself with the boss at the top, but to the longitudinally arched construction throughout its length.

100
105
110

and to the transversely arched and bossed construction near its-ends. Near the top of the channel bar at intervals along its length are sets of perforations 14 arranged for reception of the lowermost coil of the coil springs 15. The extreme ends of these springs after passing through the perforations may be bent to prevent accidental displacement. The springs are attached to the top border wire and to each other by means of such appropriate clips as are usually used in cushion seat construction.

Another means which may be used to prevent longitudinal movement of the channel bar on the bottom wire is that shown in Fig. 6. As illustrated, the swaged portions 13, formed by a punch or the like are spaced apart a distance corresponding to the width of the flattened end of the channel bar. The upset portions formed by the punch secure the channel bar in place.

The strength and durability of the channel bars or angle irons used is due not only to their general inverted U or V shape with the longitudinal reinforcing boss along the top and their longitudinally arched construction, but also to the transverse arches formed near their ends, these latter arches being provided with reinforcing bosses—an important feature. The ends of the channel bars are securely held in place by the upset portions which prevent longitudinal movement on the border wire and by the

wide bearing surface presented by the flattened ends.

What I claim is:—

1. In a cushion or seat having springs and a lower border frame, arched channel bars having flattened ends wrapped around the lower border frame and provided at intervals along their lengths with sets of perforations for reception of the lower ends of the springs, the said channel bars being arched transversely at a point near their ends for reinforcement purposes and to provide a space for a tool to wrap the flattened ends around the lower border frame, the said transversely arched portions being provided with a longitudinal bead extending the length thereof.

2. In a cushion or seat having springs and a lower border frame, longitudinally arched spring supporting bars having flattened ends wrapped around the lower border frame, the said bars being additionally arched transversely at points adjacent their ends, and a continuous bead extending the entire length of each bar to the point of its engagement with the lower border frame, whereby that portion of the bar adjacent the border frame is reinforced both longitudinally and transversely.

In testimony whereof, I have hereunto affixed my signature.

CHARLES P. TRIMBLE.
